John C. C. 1860

Des. 1627

John Gault, of Boston, Mass.
Letters Patent No. 1627, dated Aug. 12, 1862.

The schedule referred to in these Letters Patent and making part of the same.

To all whom it may concern:

Be it known that I, John Gault, of the City of Boston, in the County of Suffolk, State of Massachusetts, have invented a new and original design for enclosing government stamps used for currency, and the following is a full and exact description of the same, reference being had to the drawings making part of this specification.

My invention consists in the form of a simple metallic circular case, to contain the Government stamp; the face being open as shown.

The opening in the faceplate of the case conforming to the configuration shown in the several Figures of the drawing.

What I claim as a new design and desire to secure by Letters Patent, is

A circular metallic case, to contain a postage or Government stamp, to be used for currency, the configuration of the open face plate, being as herein described and represented.

Witnesses,

Edm F. Brown, }
E. D. Seely }

ess.

John Gault.
